(57) **CLAIM**

The ornamental design for an augmented reality head mounted display, as shown and described.

DESCRIPTION

FIG. 1 is a perspective view of an augmented reality head mounted display;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

Lines having a long dash followed by two shorter dashes indicate tangent edges. Other broken lines, e.g., dashed or dotted lines, are used to depict features or elements that are not considered to be part of the claimed design.

1 Claim, 8 Drawing Sheets
